UNITED STATES PATENT OFFICE.

THOMAS B. RICE, JR., OF PHILADELPHIA, PENNSYLVANIA.

ATTACHMENT FOR MACHINES FOR DRIVING FASTENERS.

1,153,955.

Specification of Letters Patent. Patented Sept. 21, 1915.

Application filed June 6, 1914. Serial No. 843,327.

To all whom it may concern:

Be it known that I, THOMAS B. RICE, Jr., a citizen of the United States, residing in the city and county of Philadelphia, State 5 of Pennsylvania, have invented a new and useful Attachment for Machines for Driving Fasteners, of which the following is a specification.

My invention consists of an attachment 10 for machines for driving fasteners by means of which the two articles to be united can be held with their edges suitably guided and abutting while the fastener is driven into the boards.

15 It further consists of means for feeding the articles with their edges firmly abutting beneath the driving mechanism for the fasteners.

20 It further consists of other novel features of construction, all as will be hereinafter fully set forth.

25 The annexed drawings and the following description set forth in detail one mechanical form embodying the invention, such detail construction being but one of various mechanical forms in which the principle of the invention may be used.

30 In said annexed drawings—Figure 1 represents an end view of a machine for driving fasteners embodying my invention, with the support for the articles, such as boards, shown in section. Fig. 2 represents a plan view of the board-feeding and supporting means and removed from the driving mechanism. Fig. 3 represents a side-view of said parts. Fig. 4 represents a view of two joined boards.

35 Similar numerals of reference indicate corresponding parts in the figures.

40 Referring to the drawings, the reference numeral, 1, indicates a machine of any desired or required construction for driving fasteners into the adjacent edges of two boards, which machine is illustrated as 45 adapted to sever a strip, 2, of sheet-metal into short lengths, 3, which are driven into the abutting portions of the boards, 4 and 5, from one face of the same, as illustrated in Fig. 4 of the drawings. While the fasteners are illustrated as pieces of corrugated sheet-metal driven edgewise into the wood, it is evident that any fastener which crosses the abutting edges of two articles and holds them together may be used.

55 A stationary platen, 6, is carried by a

suitable support or frame, 7, beneath the driving mechanism, which latter has a vertically reciprocated plunger, 8, beneath which the fastener strip is fed by a feeder, 9, and is cut into suitable lengths which it drives into the boards to be joined. A hopper, 10, is supported above the platen and is adapted to contain a stack of boards to be joined, such boards being stacked in pairs and with their edges adjoining. A plunger, 12, is reciprocable in the bottom of the hopper to successively push two boards out of the latter and onto the portion of the platen beneath the driver. The portion, 27, of the stationary platen upon which the one stack 70 of boards rests, is raised slightly above the level of the other portion, so that the meeting edge of the lowermost board of the adjoining stack of boards bears against the raised edge of the raised portion, and a movable platen, 14, is guided in an opening, 15, in the raised portion of the stationary platen to move vertically in the same and the inner edge of said movable platen is in the line of the joining edges of the boards to be 75 united, so that the edge of one board will abut against the said edge of the movable platen which is normally slightly raised above the level of the depressed portion of the stationary platen and upon which movable platen the other board rests, the levels 80 of the movable platen and of the raised portion of the stationary platen being the same. The moving platen has depending flanges, 16, through which pass bars, 17, each secured at one end, in the present instance, to the under side of the stationary platen, passing through slots, 18, in flanges, 19, depending from the edges of the opening for the movable platen. The opposite ends of the 85 bars 17 are resiliently supported, and, as here shown, are provided with openings in their said free ends movable upon bolts, 20, carried upon the under side of the stationary platen and having coiled springs, 21, bearing against said bars, and nuts, 22, upon the bolts, serve for adjustment of said springs 90 21. Springs, 23 and 24, are secured with their ends upon the stationary platen at the sides of the hopper and extend toward a 95 point beneath the driver and converge normally toward each other with their curved free ends, 25, and 26. The spring 23 is 100 preferably stiffer and stronger than the opposed spring. 105

In practice, the boards are stacked in pairs in the hopper with their joining edges in suitable relation. When the lowermost pair of boards are pushed out by the plunger and slid over the platens, one, as 4, will have its inner edge forced against the edge of the raised movable platen by the stiff spring 23, which it has pushed outward, so that the inner edge of the board 4 will bear against the edge of the movable platen which is raised and held so by the bars and springs, and will be held truly against the edge of the other board which rests upon the movable platen and is held against the opposite board by the spring 24 bearing against its outer edge. The plunger is now depressed and drives one or more fasteners into the boards and secures the abutting edges. A pair of the boards can be fed forward to insert fastenings one set after another, and the springs will hold the edges of the boards together. Each time the plunger is depressed and drives in a fastener or fasteners, the movable platen and board carried thereby are depressed even with the stationary platen, that is, the faces of the movable platen and the lower stationary platen are brought into alinement, and the boards will be united with their joined edges tightly drawn against each other and their faces level with each other. The lateral spring supports and the board being alined by bearing against the edge of the movable platen and having the edge of the other board forced against its edge will insure an automatic and perfectly true fit of the edges of the two boards, so that the operator of the machine is merely required to look after the feeding of boards into the hopper and successive feeding of the pairs of boards out of the bottom of the hopper by the reciprocating plunger.

Other modes of applying the principle of my invention may be employed for the mode herein explained. Change may therefore be made as regards the mechanism thus disclosed, provided the principles of construction set forth, respectively, in the following claims are employed.

Having thus described my invention, what I claim as new and desire to secure by Letters Patent, is:—

1. In a device of the character stated, a rigid platen, a platen movably supported in suitable relation to said rigid platen, one of said platens having its face normally above the face of the other and having a guiding edge, and yielding guiding means arranged to bear against the members to be united, and to hold their edges abutting and to hold the edge of one of said members in contact with said guiding edge.

2. In an attachment for machines for driving fasteners, a rigid platen, a platen yieldingly supported to have its face nor-

mally above the face of the rigid platen and having a guide-edge, and yielding guide-means arranged to bear against the members to be united to hold their joining edges together.

3. In an attachment for machines for driving fasteners, a rigid platen, a platen yieldingly supported to have its face normally above the face of the rigid platen and having a straight guide-edge, and yielding guides arranged to have their guide-portions at opposite sides of said guide-edge and adapted to bear against the outer edges of the members to be united to hold their joining edges together.

4. In an attachment for machines for driving fasteners, a rigid platen, a platen yieldingly supported to have its face normally above the face of the rigid platen and having a guide-edge, yielding lateral guides at opposite sides of said guide-edge, a hopper adapted to have the members to be united stacked within it and having a discharge opening, and a plunger slidable across the bottom of said hopper and in alinement with the discharge opening.

5. In an attachment for machines for driving fasteners, a rigid platen, a platen movable in its relation to the latter and formed with a guide-edge, means for yieldingly and resiliently supporting said movable platen to normally maintain its upper face above that of the rigid platen, and springs suitably secured on opposite sides of the guide-edge and having ends adapted to bear against the outer edges of the members to be united.

6. In an attachment for machines for driving fasteners, a rigid platen, a platen movable in the latter and formed with a guide-edge, a spring-support beneath said movable platen and normally supporting the same to have its upper face above that of the rigid platen, springs secured at their ends and having their free ends converging toward the guide-edge from opposite sides and curved to bear against the outer edges of the members to be joined, a hopper having an opening at its bottom, and a plunger reciprocable across the bottom of said hopper.

7. In a machine for fastening wooden pieces, the combination of a suitable frame, a table supported thereon, an apron carried thereby and provided with a centering edge and means mounted on the table for coating with a pair of wooden pieces, to bring them into position against said centering edge to receive a fastener.

8. In a machine for fastening wooden pieces, in combination with a supporting table, an apron carried thereby and having a centering edge, yielding means for holding the centering edge in position, and means for rendering the centering edge ineffective.

against the action of the said yielding means.

9. In a machine for fastening wooden pieces, in combination with a supporting table, an apron carried thereby and having a centering edge, and means on both sides of said centering edge for bringing together a pair of wooden pieces against the centering edge to be fastened.

10. In a machine for fastening wooden pieces, in combination with a supporting table, an apron carried thereby and having a centering edge and springs on opposite sides of the centering edge for bringing to-

gether the wooden pieces against the centering edge to be fastened. 15

11. In a machine for fastening wooden pieces, in combination with a supporting table, an apron carried thereby and having a centering edge and springs of different strength for bringing together the wooden pieces to be fastened against the centering edge. 20
